SELF-IGNITING CIGARETTE

Alfred D'Annunzio, Roosevelt, N. Y., Antonio D'Annunzio, Giuseppe De Blasio, and Concetta Calderone, administrators of said Alfred D'Annunzio, deceased

Application February 27, 1941, Serial No. 380,931

1 Claim. (Cl. 131—7)

This invention relates to self-lighting cigarettes, particularly of the type having a striking tip which ignites upon frictional engagement with a striking surface.

While many type of self-lighting cigarettes have heretofore been developed, certain deficiencies have inhibited their development. It is an object of this invention to correct these deficiencies by providing, first, a cigarette of this type having a striking tip which, when ignited, will not flare up in the direction of the body of the cigarette.

Another object is to form a striking tip in the end of a cigarette, which tip will not fall or be knocked off upon striking.

Still another objective is the provision of a self-igniting cigarette having the appearance of an ordinary cigarette, and being so constructed as to utilize the same size and type package used for ordinary cigarettes.

Most particularly, it is proposed herein to provide a self-lighting cigarette having a striking tip of material which, upon combustion thereof, will not alter or impair the flavor of the tobacco in the rest of the cigarette, and, further, will give off no noxious odors.

A further object is to provide a cigarette of this type in which, when the striking tip is ignited, the tobacco forming the cigarette is necessarily ignited, whether or not the cigarette be immediately smoked.

Another proposal is to provide a cigarette of this type which is inexpensive to make, which is subject to production by machinery, and the formation of which may be carried out in continuous, uninterrupted steps. These and other objectives will be apparent from the following specification and drawing, in which—

Fig. 1 is a perspective view showing the new cigarette;

Fig. 2 is an end view showing the striking tip, and

Fig. 3 is a cross-section taken vertically through the middle of the striking end of the cigarette.

Referring to the drawing, the reference numeral 2 denotes the self-striking cigarette formed of the usual tubular paper wrapper 4 encasing tobacco. In this respect, the cigarette 2 is similar to any one of a number of well-known brands of cigarettes now on the market. In the end of the cigarette which is to be lit, however, there is embedded a striker formed of two portions, namely, a base 8 and a striker 10.

Base 8 is formed of deflagrating material, namely, a mixture of chlorate of potash, tobacco, and antimony sulphide, with a small portion of emery, mixed with sufficient adhesive binder, such as gum arabic or gum tragacanth to form a plastic pasty mass.

5 Base 8 is applied by forming a small indentation in the end of the cigarette, and then pressing a pellet of the plastic, pasty mass into the indentation. The indentation is formed, preferably, by a conical tool pressed, point first, into the end of the cigarette so as to form a substantially conical recess. The pellet is of such size as substantially to fill the recess. When pressed into the recess, the material in the pellet, which forms base 8, commingles with the tobacco 6 in the remainder of the cigarette so that when the binder hardens, the tobacco shreds in the base are bonded to the shreds of tobacco forming the remainder of the cigarette, thus to anchor the base firmly in the cigarette. A further feature of this step is that the paper at the end of the cigarette is in no way affected by the binder.

20 Finally, the striker 10, comprising a pellet of chlorate of potash, antimony sulphide, emery, and sufficient adhesive binder, such as gum arabic, to form a pasty, plastic mass, is placed on base 8, with which it becomes an integral part.

The cigarette may be ignited by rubbing the 25 striker 10 against any suitable striking surface of the type conventionally used on safety-match boxes. Preferably, such a striking surface is provided on the cigarette package.

When ignited, the striker 10 ignites base 8, which, together with the tobacco mixed therein, rapidly combusts and ignites the tobacco in the end of the cigarette. Flaring to the sides or rearwardly is prevented by the tobacco surrounding base 8 and, simultaneously, positive ignition of such tobacco is assured.

30 The invention having been thus described, it is intended that this invention be not limited to the specific disclosures, but only by the following claim.

40 What I claim and desire to secure by Letters Patent is:

A self-lighting cigarette, comprising a tubular wrapper, tobacco shreds therein, said shreds at one end of the wrapper being spaced from the 45 edge thereof and having a conical recess formation in the central portion of that end, a pellet consisting of shredded tobacco, adhesive binder, and other burnable material completely filling the recess and peripherally spaced from the interior surface of the wrapper on all sides, and a striker of ignitable material secured to the pellet and projecting outwardly past the edge of the cigarette, the maximum width dimension of the striker being substantially less than the smallest transverse dimension of that portion of the pellet facing outwardly at that end of the cigarette in which the pellet is located.

ALFRED D'ANNUNZIO.
